UNITED STATES PATENT OFFICE.

DANIEL L. GEARNER, OF DUFF, INDIANA.

RAIL JOINT.

Application filed September 13, 1923. Serial No. 662,492.

To all whom it may concern:

Be it known that I, DANIEL L. GEARNER, a citizen of the United States, residing at Duff, in the county of Dubois and State of Indiana, have invented certain new and useful Improvements in Rail Joints, of which the following is a specification.

The present invention relates to a rail joint.

10 The main object of the invention is to construct the fish plates of the joint so that they will engage the top and bottom of the foot of the rail and in this manner support the adjacent rail ends at the joint. One of the 15 fish plates is accordingly provided with a base resting directly on a tie and upon this base the rail is seated.

In the accompanying drawing one embodiment of the invention is illustrated, and—
20 Figure 1 is a perspective view of the rail joint before assembling, and

Figure 2 is a transverse section of the rail joint in position.

In the drawings, the reference numeral 25 10 represents a tie above which the two ends 11 and 12 of the rails meet. The rail joints are provided in pairs comprising a base member 13 and a securing member 14. The base member includes a fish plate 15 which 30 is arcuate in cross section. The said fish plate continues downwardly with an inclined flange 16 adapted to engage with the top of the rail foot 17. At the lower end of the flange 16 the base plate 18, integral 35 therewith, is turned inwardly and has sufficient width to support the entire width of the foot 17. The base plate 18 does not need to have the full length of the flange 16 but is preferably considerably shorter. The top 40 edge 19 of the fish plate is flat or blunt in order to engage with the inclined lower side of the rail head 20. The inner side of the fish plate is recessed, as at 21, so that it stands away along a horizontal central line 45 a considerable distance from the neck 22 of the rail.

The securing member 14 is shaped in a similar manner to the base member 13 and consists of a fish plate 23 continuing downwardly with the flange 24 and terminating with a narrow foot 25 adapted to rest on the tie 10. The securing member does not, however, have an inwardly turned base plate like the base member 13 and is not intended 55 to abut against the edge of the base plate 18

when assembled, a narrow space 26 being formed between the latter and the foot 25.

Both fish plates 15 and 23 are provided with a series of transverse apertures 27 in which the clamping bolts 28 are adapted to engage, as well as in corresponding apertures 39 provided through the necks 22 of the rails. When the nuts of these bolts 28 are drawn up tightly the arcuate fish plates 15 and 23 will expand in vertical direction to 65 engage tightly between the head 20 and the foot 17 of each rail.

The flanges 16 and 24 are also provided with apertures 29 and 30 adapted to receive 70 the rail spikes 31.

This rail joint provides a very firm connection between the rail ends and gives a very good support for the same. It is evident that when rails have to be replaced, it is only necessary to loosen the nuts of the 75 bolts 28 and remove the securing member 14 after the spikes 31 holding the latter to the tie have been taken out. The base member 13, however, does not need to be disturbed but remains in position on the tie 80 without removing the spikes 31. By this arrangement the advantage is gained that no adjustment of the rails need take place because the new rails will be alined in the stationary rail joint member 13. Ordinarily, 85 a track gage is necessary for this relaying of rails but in the present instance the firmly secured joint members 13 provide a gage for the distance between each pair of rails.

Having thus described the invention, what 90 is claimed as new is:

1. In a railroad track having ties, a rail joint comprising a pair of arcuate fish plates, an inclined flange along the lower edge of each fish plate, a base plate integral 95 with the flange of one of said fish plates medially positioned thereon and extending substantially the full width under the foot of the rail and the full width of the supporting tie, the flange of the other fish plate terminating with a narrow foot adapted to rest on said tie and having spaced relation with said base plate in assembled position, and means for securing the fish plates to the rail.

2. In a railroad track having ties, a rail 105 joint comprising a pair of arcuate fish plates, an inclined flange along the lower edge of each fish plate, a base plate integral with the flange of one of said fish plates medially positioned thereon and extending 110

substantially the full width under the foot of the rail and the full width of the supporting tie, the flange of the other fish plate terminating with a narrow foot adapted to rest on said tie and having spaced relation with said base plate in assembled position, the top edges of said fish plates engaging under the head of the rail and the flanges standing on the top of the rail foot while the opposing 10 inner sides of the fish plates are spaced from

the neck of the rail; and bolts adapted to clamp the fish plates securely to the rail, said fish plates being provided with suitable apertures for said bolts and said flanges, a narrow foot and base plate having apertures 15 situated adjacent the edges of the rail foot and adapted to receive rail spikes.

In testimony whereof I affix my signature.

DANIEL L. GEARNER. [L. S.]
